UNITED STATES PATENT OFFICE.

PAUL T. J. ESTLER, OF LONDON, ENGLAND.

STORE-BIN.

No. 873,664.

Specification of Letters Patent.

Patented Dec. 10, 1907.

Application filed April 15, 1907. Serial No. 368,373.

To all whom it may concern:

Be it known that I, PAUL TRAUGOTT JU-
LIUS ESTLER, a subject of the King of Great
Britain and Ireland, whose postal address is
5 25 Lawrence Pountney Lane, Cannon Street,
London, E. C., England, engineer, have in-
vented certain new and useful Improvements
in Store-Bins, of which the following is a
specification.

10 The object of this invention is to increase
the holding capacity of well-shelves or store
bins, used for the storage of bolts, nuts, small
castings, component parts, metals, grain and
other materials; and to permit easy inspec-
15 tion of the contents, and to facilitate the in-
sertion and removal of the articles. The bins
being so constructed that they can be easily
dismounted and the component parts packed
in a small space for shipment and be readily
20 reassembled when reaching their destination.

In order that this invention may be more
easily understood reference is made to the
accompanying drawings in which like figures
represent like parts.

25 Figure 1, is a cross section of a simple nest
of bins. Fig. 2 is a cross section of a double
nest of bins, in perspective. Fig. 3, is a front
elevation of Fig. 1 partially fitted.

The arrangement consists of a series of ver-
30 tical partitions *a*, strung together on horizon-
tal rods *j*, the wells or bins *h*, between each
vertical partition *a*, being of sheet metal bent
to form a vertical back, a flat floor extending
approximately half way across, and a front
35 portion sloping upwards and forwards to a
height approximately half that of the ver-
tical back (or of any other desired propor-
tions as circumstances may require). The
top edge of the back and the top edge of the

front being bent over forming a lip or hook *k*, 40
that rests upon the horizontal rods *j*, con-
necting the vertical partitions *a*.

Any convenient number of vertical parti-
tions can be strung together, and any con-
venient number of wells can be superposed; 45
when the wells are hooked upon their respec-
tive rods, the whole nest can be firmly se-
cured together by tightening the nuts *c*, at
the ends of the horizontal rods. It will be
obvious that by slackening the nuts *c*, the 50
wells can be lifted off the rods and placed one
within the other, and when the rods are
withdrawn the whole can be packed into a
small space for shipment, and as all parts are
interchangeable they can be easily re- 55
mounted. This is partially illustrated in
Fig. 3 which shows the wells in position in
the two outer divisions and the wells re-
moved from the center division.

Having now described my invention, what 60
I claim as new and desire to secure by Letters
Patent is

Store bins consisting of vertical partitions
strung together on horizontal rods support-
ing wells or troughs of sheet metal bent to 65
form vertical backs, floors partially flat, and
fronts sloping upwards and forwards, the up-
per edges of the backs and fronts being bent
into lips or hooks that engage with the hori-
zontal rods connecting the vertical parti- 70
tions, the whole being secured together by
tightening the nuts at the ends of the hori-
zontal rods.

Dated this the 5th day of April 1907.
P. T. J. ESTLER.
